UNITED STATES PATENT OFFICE.

JAMES H. BOYE, OF CHICAGO, ILLINOIS.

DESIGN FOR A CURTAIN AND PORTIÈRE ROD.

Application filed March 5, 1928. Serial No. 25,670. Term of patent 7 years.

To all whom it may concern:

Be it known that I, JAMES H. BOYE, a citizen of the United States, residing at Chicago, in the county of Cook and State of Illinois, have invented a new, original, and ornamental Design for Curtain and Portière Rods, of which the following is a specification, reference being had to the accompanying drawing, forming part thereof.

I claim:

The ornamental design for a curtain and portière rod, as shown.

JAMES H. BOYE.
